UNITED STATES PATENT OFFICE.

ARTHUR L. GEORGE, OF JOHNSTOWN, PENNSYLVANIA, ASSIGNOR TO
THE LORAIN STEEL COMPANY, OF PENNSYLVANIA.

DERAILING-SWITCH.

SPECIFICATION forming part of Letters Patent No. 639,373, dated December 19, 1899.

Application filed July 27, 1899. Serial No. 725,285. (No model.)

To all whom it may concern:

Be it known that I, ARTHUR L. GEORGE, of Johnstown, in the county of Cambria and State of Pennsylvania, have invented a new and useful Improvement in Derailing-Switches, of which the following is a full, clear, and exact description, reference being had to the accompanying drawings, which form a part of this specification.

This invention has relation to switches of that class generally known as "derailing-switches," which are designed for use where an electric or street car track crosses a steam-railroad or at other danger-points for the purpose of compelling a car approaching the crossing to stop before proceeding over the crossing or by the danger-point, and thereby lessen to a great extent the occurrence of accidents.

The object of the invention is to provide a switch of this character with means whereby the switch tongue or point is normally positively locked in a position to divert an approaching car from its main track to siding or turnout rails and whereby such lock cannot be released except at a point in advance of the car and upon the distant side of the crossing or other danger-point, the releasing means, however, being independent of any means for throwing the switch-tongue to its opposite position or in position to pass the car, which can only be done at the switch itself, and the invention is herein distinguished from those switches heretofore used wherein the switch is thrown from a tower or other distant point.

A further object of the invention is to provide means whereby the car after passing the switch is caused to set in operation devices for automatically returning the switch-tongue to its normal diverting position.

Other objects relate to the simplification in construction and arrangement of the parts employed in carrying into effect the above-named objects and to provide means therefor of practical and inexpensive character which can be used in connection with any ordinary pivotal switch-tongue.

With these objects in view my invention consists in the novel construction and combination of parts, all as hereinafter described,

and pointed out in the appended claims, reference being had to the accompanying drawings, in which—

Figure 1 is a plan view showing the application of my invention. Fig. 2 is an enlarged plan view showing the switch proper, the lock therefor and its adjuncts, and the means operated by a passing car for resetting the lock, the covers of the respective boxes inclosing the operating devices being removed. Fig. 3 is a sectional plan view of the locking devices. Fig. 4 is a side elevation of the same with the box in section. Figs. 5 and 6 are detail views of one of the wedges. Fig. 7 is a sectional plan view of the resetting devices. Fig. 8 is a section on the line A A of Fig. 7. Fig. 9 is a side elevation showing the manner in which the box containing the resetting devices is secured to the rail. Fig. 10 is a detail view. Figs. 11 and 12 are detail views showing a modification of the locking device. Figs. 13 and 14 are detail views of the parts at the distant side of the crossing.

In the drawings the letter A designates the main rails of the electric road or street-track, B the siding or turnout rails, and C the rails of the steam-track.

D is a switch-tongue of the usual pivoted style and which is normally set in position to divert an approaching car onto the rails B.

D' designates a suitable box or closure which is set in the road-bed against the switch structure (to which it is usually bolted) at a point between the heel and point of the switch-tongue and nearer to the point than to the heel.

E is a bell-crank or rocker which is sleeved within said box on a pin c, supported in lugs c' and having the arms E' E''. The arm E' is bifurcated, as shown in Fig. 4, and the end portions of its furcations are provided with open slots e.

F designates a block or stud having pins or studs f f projecting from its top and bottom surfaces and engaging the slots e of the arm E'. Said block has at one side a laterally-projecting rod or stem F', which extends out through one side of the box or closure D' and through an opening in the switch structure in position for contact with the side of the switch-tongue, as shown. The opposite side

of said block is formed with a wedge-face F^2 , which coacts with the similar, but shorter, face G' of a second block G , having at the lower side of said face a shoulder g .

5 F^3 is an antifriction-roller against which one edge of the block F bears in its movement toward and away from the switch-tongue. The block G has a downwardly-extending arm G^2 , by means of which it is made fast to a rod 10 H in the lower portion of the box D' . The outer edge of the said block also has a bearing against an antifriction-roller G^3 , journaled in bearings g' on the side of the box.

The rod H , which is provided with guides in 15 projections D^3 and D^4 of the box D' , has coiled about it a spring I , bearing at one end against the wall of the projection D^4 and at the opposite end against the arm G^2 of the block G .

20 K is a second spring, which is coiled about the rod or stem F' , above described, with a bearing at one end against the block F and at the other end against the wall of the box D' , its action being to keep the wedge-face of the blocks F and G in contact with each other and 25 to cause the block F to recede from the switch-tongue as the block F is moved to the right, (looking at the drawings G ,) as herein-after more fully described.

Connected to the rod H is a cable L or its 30 equivalent which extends through a suitable protective casing L' to a point on the opposite side of the crossing, where it enters a second box L^2 , set in the road-bed or adjacent thereto, and is connected to the depending 35 arm of a rocker L^3 . The rocker L^3 is journaled transversely in open bearings l on the inner sides of the box L^2 and is formed with a socket l^2 to receive a suitable operating-bar. (Not shown.)

40 N designates a third box or closure, which is set in the road-bed and fitted and bolted to one of the main rails A , a part upon each side thereof. Pivoted at one end portion at o within the said box and having suitable 45 guides P' is a wheel-plate O , having a beveled edge o' for contact with the wheel-flange and normally held against the rail-head by the action of a spring P . Rigidly connected to a depending lug or flange of the said plate is a 50 stud R , which projects laterally through an opening r in the web of the rail B and is pivotally connected at s to an arm S' of a bell-crank or rocker S , sleeved on a pin or bolt s' . Connecting the other arm S^2 of said bell-crank or rocker with the arm E^2 of the bell-crank or rocker E , above described, is a rod T . 55

60 The manner of operation is as follows: The switch being normally set to divert the car from the main track and positively locked in that position by the contact of the switch-tongue with the rod or stem F' of the wedge-block F , a car must always stop before proceeding to the crossing and the conductor or other employee must precede the car to the 65 other side of the crossing, where by means of a suitable bar inserted in the socket l^2 of the rocker L^3 he actuates the connection L , rod

H, and wedge-block G to withdraw the inclined face of the latter from contact with the similar face of the block F . As the block G 70 is thus withdrawn, the spring K acts to force the block toward the outer wall of the block or casing D' until it engages with the shoulder g of the block G . This engagement locks the block G against return movement and 75 holds the spring I under compression. The described movement of the block F has withdrawn the rod or stem F' a sufficient distance from the switch-tongue to permit the latter to be thrown to position to pass the car, which 80 is done by the motorman of the car by means of a bar such as is usually employed for this purpose. The car now proceeds, and in passing the box N the wheel-plate O by the action of the wheel-flange is moved away from the 85 rail B , and this movement, through the rocker S and rod T , actuates the rocker E to move the wedge-block F toward its normal position and release its engagement with the shoulder g of the block G . This, it will be seen, releases the spring I , which immediately moves the block G back to normal position, and thereby completes the return movement of the block F to reset the switch-tongue and again 90 lock it. 95

It will be observed that I do not depend altogether upon the action of the passing car to reset and lock the switch, but that I supplement such action with the action of the spring I . The principal reason for this is found in 100 the fact that the wheel-flanges vary considerably in thickness, and if the parts were arranged to have a sufficient degree of movement to fully reset the tongue under the action of a thin wheel-flange the action of a 105 thicker flange would result in breakage. The arrangement which I have shown and described clearly avoids all difficulty of this kind.

Inasmuch as the device forms a positive 110 lock for the switch-tongue until released at the distant side of the crossing, the tongue will not trail to pass a car in the opposite direction, and the arrangement is therefore applicable only to double-track roads, as shown 115 in Fig. 1. By a slight modification now to be described the device may, however, be readily adapted to single-track use. In such modification in lieu of the rod or stem F' , rigidly secured to the wedge-block F , I secure a similar rod or stem W to the switch-tongue and provide in the block F a recess w to receive the end portion of the same. In lieu of the spring K , seated at one end against the wall of the box D' , I employ a heavier spring W' , 120 seated at one end against the wedge-block F and at the opposite end against a pin or collar w' on the stem W . The operation, while similar to that of the form first described, is slightly different in detail. The lock is released 125 by the distant operator in the same manner as above, the block F moving laterally away from the rod or stem W under the action of the spring W' and into locking en- 130

gagement with the block G. The motorman can now throw the tongue and permit the car to pass. As the car proceeds the wheel-plate O is actuated, thereby releasing the lock between the blocks F and G. The return movement of the block F, effected in part by the spring I and in part by the rocker E, puts the spring W under compression, the spring W acting to return the switch-tongue to its normal diverting position. The socket W, it will be readily seen, permits the tongue to trail and pass a car in the opposite direction.

In neither of the forms above described is it necessary for the distant operator to hold the lock released until the car has passed, this being automatically effected by the lock between the wedge-blocks.

For the sake of brevity and convenience I have herein and in the appended claims used the word "tongue" to designate the movable member of the switch. I do not by this, however, limit the invention to any particular form of switch, and the term should be understood as applying generally to the movable member of a switch whatever may be its particular character.

I do not in this application, claim broadly, a switch having a lock which cannot be released except from a distant point and which when so released cannot be operated except from the switch, as this forms the subject-matter of another application of even date herewith, Serial No. 725,333. I do not, however, desire to limit myself in this application to the particular construction and arrangement of parts which I have shown and described, as the same may be varied in detail without departing from the spirit and scope of my invention.

Having thus described my invention, what I claim, and desire to protect by Letters Patent, is—

1. The combination with a switch normally set to divert a car from its main track, of a lock for normally holding the movable member of the switch in said position, means operable at a distant point for releasing the said lock, automatic devices for holding the said lock in released position, and means for releasing said devices, resetting the switch, and relocking the same after a car has passed.

2. The combination with a switch normally set to divert a car from its main track, of a lock for normally holding the movable member of the switch in such position, means operable from a distant point to release the said lock, automatic devices for holding the lock released while a car is passing, and means operated by the passage of the car for automatically resetting and relocking the switch.

3. The herein-described means for compelling a car to stop before passing a crossing or other danger-point, comprising a switch normally set to divert a car from its track and locked in that position, means whereby the lock can be released only from a place in ad-

vance of the crossing or other danger-point and whereby the switch when released can be operated only from the place where it is situated, and means for automatically resetting 70 the switch and relocking the same after a car has passed.

4. In a safety-switch of the character described, the combination with a main track, siding or turnout rails, and a switch-tongue 75 set to normally divert a car from the main track to said siding or turnout rails, of a lock for holding said tongue so set, means for releasing said lock at a distant point without throwing the switch-tongue to its other position, means whereby the said tongue when thrown is automatically locked in that position while the car is passing, and means operated by the further movement of the car for releasing the last-named lock, for resetting 85 the switch-tongue to normal position, and for restoring the first-named lock.

5. In a safety-switch, the combination with a switch-tongue normally set to divert an approaching car from its track, of coöperating 90 wedge devices which normally lock said tongue in that position, means connected to one of said devices for actuating it in one direction from a distance, a spring for actuating said device in the reverse direction, means 95 for locking said device against the action of the said spring, and means operated by the passage of the car for releasing the last-named lock.

6. In a safety-switch, the combination with 100 a switch-tongue normally set to divert a car from its track, of coöperating wedge devices, one of which has a rod or projection normally engaging said tongue and locking the same against movement, means connected to the 105 other of said devices for actuating it from a distant point, means for effecting a lock between the said devices, and car-operated means for releasing said lock and returning the parts to their normal positions. 110

7. In a safety-switch, the combination with a switch-tongue normally set to divert a car from its track, of a device having a rod or stem normally in locking contact with the switch-tongue, and having a wedge portion, 115 a coöperating wedge-piece, means connected to said piece for operating the same from a distance to release the said device, a spring for retaining said piece, means for restraining the operation of said spring, and car-operated devices for releasing the restraining means. 120

8. In a safety-switch, the combination with a switch-tongue normally set to divert a car from its track, of a wedge having a rod or 125 stem for contact with the said tongue, a co-operating wedge, means connected to the latter for actuating it from a distance in one direction, a spring for actuating it in the reverse direction, means for effecting a lock 130 between said wedges for restraining the action of said spring, a rocker device engaging

the first-named wedge, and means located in advance of the switch and operated by the passing car for actuating said rocker device.

9. In a safety-switch, a pair of coöperating wedges, one of which has a rod or projection normally engaging the movable member of the switch to lock the same in position to divert a car from its track, and the other of which has a shoulder for engagement with the first and also means connected thereto for operating it in one direction from a distant point, a spring for effecting a reverse movement, a rocker engaging the first-named wedge, a pivoted wheel-plate in advance of the switch, and a connection between said plate and the rocker.

10. The combination with a switch normally set to divert an approaching car, means for normally locking the same, means for releasing said lock at a distance and means for holding the same released until the car has passed the switch, of a wheel-plate located in advance of the switch to be actuated by the wheel-flanges of a passing car, and connections whereby the movement of said plate releases the holding means, and means for resetting the switch-lock upon the said release.

11. The combination with a switch normally set to divert an approaching car, a laterally-movable wedge having a rod or stem which forms a lock for said switch, a longitudinally-movable coöperating wedge, manually-operated means for actuating the last-named wedge from a distance in one direction, a spring for actuating the same in the reverse direction, a spring for actuating the laterally-movable wedge in one direction, and car-operated means for actuating it in the reverse direction.

12. The combination with a switch nor-

mally set to divert an approaching car, means for locking the same, means for releasing the lock from a distant point to permit the switch to be thrown at the point where it is situated, and means for holding the lock released until a car has passed, of means operated by the car for releasing the holding means and for partly resetting the switch, and a spring for completing the resetting of the switch.

13. In a safety-switch, the combination with a movable switch member, of a pair of coöperating wedges normally forming a lock for said member, a socketed rocker located at a distance from said switch, and on the opposite side of a danger-point, a connection between said rocker and one of said wedges, a device operated by the flange of a car-wheel and situated between the switch and the danger-point a connection between said device and the other of said wedges, and springs acting upon said wedges to move them in directions reverse to those in which they are respectively moved through said connections.

14. In a safety-switch, the combination with a movable switch member, the coöperating wedge devices forming a lock therefor, and means for releasing said lock from a distant point, of a rocker having a bifurcated arm engaging one of said wedges, a wheel-plate located in advance of the switch to be operated by the wheel-flanges of a car, a rocker adjacent thereto, and a connection between the two rockers.

In testimony whereof I have affixed my signature in presence of two witnesses.

ARTHUR L. GEORGE.
